No 725

Thomas Lewis' Design for Trade Mark.

Patented September 4, 1855.

Des. 725

Thomas Lewis, of Malden, Mass.
Letters Patent No. 725 - Dated Sept 4th 1855.

The schedule referred to in these Letters Patent and making part of the same

To all persons to whom these presents shall come.

Be it known that I Thomas Lewis of Malden in the County of Middlesex and State of Massachusetts, have invented or produced a new and original ornamental design for a "trade mark" to be either printed, painted, cast, carved, or engraved or otherwise fixed on any article of manufacture, and I do hereby declare that the same is fully represented in the accompanying drawing.

The outer boundary of said design consists of a circular fillet of dots and bars, either alone or united to a padlock, the same being in bas relief.

Within this and concentric therewith are two plain fillets extending around within the external boundary about three hundred and fifteen degrees the space between them being for such words or characters, either in bas relief or "in caro" or otherwise as circumstances or fancy may dictate.

The above members or parts surround a fancy shield edged with scroll work in relief or otherwise. This shield is surmounted by a crest which represents a griffin rampart on a curved base. Beneath the shield and flanking it is a wreath one half of which is composed of oak leaves while the other half consists of olive leaves with their stems intertwined.

I claim the above ornamental design or Trade Mark to be fixed on articles of manufacture and formed without the padlock.

In testimony whereof I have hereunto set my signature this fourth day of August A.D. 1855.
